UNITED STATES PATENT OFFICE.

WARREN W. CARPENTER, OF QUEENS VILLAGE, NEW YORK, ASSIGNOR TO WESTERN ELECTRIC COMPANY, INCORPORATED, OF NEW YORK, N. Y., A CORPORATION OF NEW YORK

TELEPHONE-EXCHANGE SYSTEM.

Application filed November 14, 1924. Serial No. 749,850.

This invention relates to telephone exchange systems, and more particularly to telephone systems wherein automatic switches and automatic switch controlling apparatus are employed for connecting subscribers' lines for purposes of conversation.

In telephone systems where idle interconnecting trunks are selected under the supervision of common controlling mechanisms, the condition sometimes arises under which two selective switches may be operated simultaneously or quite nearly so to seize the same idle trunk. In such an instance, the particular switch which possesses the more rapid operating characteristics will obviously be successful in seizing the trunk. However, when there is an appreciable interval between the initiation of the testing operation and the subsequent operation of a switch to seize this trunk, there may exist a condition in which the trunk has been tested for and found idle and during the interval elapsing before the operation of the selective switch to seize this trunk, a second selective switch may attempt to seize the same trunk.

It is an object of the invention, therefore, to render a trunk, which appears before a number of switches possessing different operating characteristics, non-selectable during the period subsequent to the recording of an idle condition of said trunk and prior to the operation of said switch to seize the trunk.

A feature of the invention relates to a common registering mechanism which records the idle condition of any one of a number of trunks, together with the novel means for nullifying said record when said trunk has been seized subsequent to the recording of its idle condition.

A still further feature resides in the means for multiplying trunks before switches of different types.

Another feature of the invention relates to a telephone system wherein different types of switches are employed in completing connections wherein each trunk of a group is selectable by a switch of any type, and wherein each of said trunks has individual means normally effective to maintain different selectable conditions thereon, and operatively effective to maintain the same non-selectable potential on said trunk at the

switches of all types, before which said trunk appears.

Other features and advantages of the invention will become apparent when the following detailed description and the appended claims have been considered.

Referring to the drawing Fig. 1 shows a plurality of subscribers' lines and a number of selective switches for interconnecting these lines. This figure also illustrates diagrammatically a sender selector, a registering and controlling sender, together with a number of multi-contact relay connecting devices.

Fig. 2 shows a portion of the testing and controlling equipment in the marker which is associable with any sender and with certain of the switches shown in Fig. 1 for controlling the operation thereof.

Fig. 1 when positioned above Fig. 2 shows a sufficient portion of a telephone exchange system, and in sufficient detail to enable an understanding to be attained of a preferred form of carrying out the invention.

The invention has been shown as applied to a telephone system employing switches of the coordinate type as well as switches of the power driven type. The coordinate selector switches 100, 150, 160 and 170 and the sender selector 110 may be of the same general construction and mode of operation as that disclosed in the British patent to the Western Electric Company, Limited, No. 183,438, accepted Sept. 6, 1923 and in the application of S. B. Williams, Serial No. 596,179, filed Oct. 23, 1922, whereas the switches 151, 152, 153 and 154 are preferably of the general character of those disclosed in the patent to A. E. Lundell, No. 1,168,319, issued Jan. 18, 1916. The sender 110, sender connector 130, frame connector 140 and trunk connector 180 are similar in construction and method of operation to corresponding elements in the copending application of Warren W. Carpenter, Serial No. 703,362, filed April 1, 1924. Inasmuch as the present invention is concerned mainly with the manner of testing for, and rendering non-selectable an interconnecting trunk, a detailed operation of the switching and controlling apparatus is not deemed necessary.

An examination of Fig. 1 of the drawing will reveal the fact that certain of the trunks extending between the coordinate

switches 150 and 160 are also multiplied before the power-driven switches 152 and 153. Two of these trunks, namely trunks 161 and 166 are shown multiplied, it being understood 5 that other trunks as 158, 159 etc. have an appearance not only in switch 150 but also in switch 152.

Detailed description.

- 10 It will be assumed that the subscriber at station 101 has initiated a call by the removal of his receiver from the switchhook. The removal of the receiver results in the automatic operation of line switch 100 whereby 15 an idle trunk as 155 is seized, and sender selector switch 110 is also actuated to associate an idle register sender as 120 with the calling line. The calling subscriber thereupon dials the designation of the wanted line 20 which results in the positioning of the several registers in sender 120. When the registers have been thus set, the sender connector 130 is actuated to associate an idle marker or switch controlling mechanism 25 partially shown in Fig. 2 with the sender. As soon as the marker has been thus associated start relay 201 is energized, and the numerical record is transferred from the registers of sender 110 to corresponding registers 250 in the marker. Upon the completion 30 of the transferring of the record from the sender to the marker the frame connector 140 and the trunk connector 180 are selectively actuated. The frame connector 140 35 associates the links of switch 150, in which trunk 155 terminates, with the marker testing mechanism shown in Fig. 2. The trunk connector 180 also associates the test conductors of the trunks in the desired group outgoing 40 from switch 150 with the same testing mechanism. At this time also the vertical operating magnets 156 and 157 are actuated. For a detailed description of the manner in 45 which the foregoing operations are effected, reference may be had to the application of Warren W. Carpenter, hereinbefore referred to.

The marker is now in readiness to test the links in switch 150 as well as the trunks in 50 the desired group which, for the purposes of description, may be assumed to include trunks 158, 159, 161, etc. With trunk vertical magnet 157 operated a circuit is completed from ground at the lower armature and contact thereof, thence by means of the frame connector 140 to battery through the winding of relay 202. Relay 202 relates to the vertical row of contacts 111 in switch 150 and serves as an indication to the marker that a 55 district trunk vertical magnet has operated. The test relays 240 are now connected to the various links and trunks in switch 150, and an appreciable interval is provided to allow 60 these test relays to take their complete setting in accordance with the busy or idle con-

dition of the links and trunks. When any of the trunks 158, 159, 161 etc. are idle, the relay 116, 117, 118, etc. individual thereto is normal. Consequently battery is connected through a right-hand non-inductive winding 141, 142, etc., back contact of the normal relay, to the sleeve conductor of the idle trunk appearing in switch 152. The presence of this battery potential upon the sleeve conductor of the trunk identifies the same, in the well-known manner, as selectable by switch 152; whereas the absence of ground on the sleeve conductor identifies the trunk as idle to switch 150 as will hereinafter appear. Should any of the trunks 158, 159, etc. 70 be seized by the operation of switch 150 the sleeve conductor is immediately grounded causing the actuation of the corresponding relay as 116 by means of the left hand winding. The actuation of this relay extends the 80 ground potential through its front contact, thereby reducing the potential on the sleeve conductor of the trunk at switch 152 and identifying this trunk as non-selectable. Should, however, trunk 162 be seized by 85 switch 152, then in the well known manner a relay as 157 operates and grounds sleeve conductor 163 thus identifying trunk 162 as non-selectable to other switches similar to switch 152 before which trunk 162 is multiplied. In this case relay 117 is normal and the non-selectable potential is not connected to the sleeve conductor of trunk 162 at 90 switch 150. However, this trunk cannot be seized by switch 150 as will be explained 95 hereinafter.

It will be assumed that link 112 is busy, and the remaining links are idle. It will also be assumed that trunk 158 is busy at switch 150, and trunk 159 is busy at switch 105 152, while the remaining trunks are idle. Accordingly relay 116 is operated, while relay 117 is normal and a circuit may be traced from battery through the right winding of test relay 204, right outer armature 110 and back contact of relay 208, conductor 251, contacts of frame connector 140, left winding of magnet 123, thence to the grounded sleeve conductor of busy link 112. The resistance of the right-hand winding of 115 relay 204 is of such a value as to prevent the energization of magnet 123 when included in series with the left winding thereof. Another circuit may be traced through the left winding of relay 204, left armature, and back contact of relay 208, conductor 252, contacts of trunk connector 180, right armature and front contact of relay 116 to the grounded sleeve conductor of trunk 158. It 120 will be noted that the energization of either one or both windings of the test relays 240 is sufficient to cause actuation of the same. Therefore, when relay 204 operates it closes a locking circuit which is completed through the left winding and the right contacts of 125 130

the said relay to ground at the left contacts of relay 201. As a result of the busy condition of trunk 159 at switch 152, the test relay 205 is energized in a circuit traceable from

5 battery through the left winding of relay 205, left back contacts of relay 209, conductor 258, contacts of connector 180 to sleeve conductor 164 of trunk 159 which is grounded by the operation of a relay similar

10 to relay 157. Relay 205 operates and locks, thus rendering trunk 159 non-selectable by switch 150. Since link 114 and trunk 161 have both been assumed to be idle, the corresponding relay 206 remains normal.

15 Accordingly, when the test relays 240 have become stabilized, a circuit is completed from battery, through the winding of relay 210, left contacts of relay 206, left armatures and front contacts of relays 205, and 204 in series,

20 conductor 254, contacts of frame connector 140, conductor 253, contacts of relay 202 to ground at the right contacts of relay 201. Should a trunk as 166 be seized by switch 152 after its idle condition has been

25 recorded on relays 240 and prior to the stabilization of these relays, the record is immediately revised by means of ground through the armature of sleeve relay 157, thence through contacts of connector 180 to cause the operation of the corresponding

30 test relay 207. The operation of relay 210 completes a circuit from ground through the winding of the common relay 212, the left armature and front contact of relay 210,

35 conductor 256, contacts of trunks connector 180, armature and back contact and non-inductive winding 143 of relay 118 to battery. Relay 212 operates in this circuit. The resistance of relay 212 is sufficiently low

40 to reduce the potential on conductor 165, rendering trunk 161 non-selectable at switch 152. A circuit is now completed for energizing the horizontal operating magnet 121 which may be traced from battery through

45 the right winding thereof, contacts of frame connector 140, conductor 255, right outer armature and front contact of relay 210, to ground at the contacts of relay 212. Magnet 121 is energized in this circuit but an interval elapses before connection is completed between trunk 155 and trunk 161 by means of link 114. During the interval while magnet 121 is operating trunk 161 is rendered

50 non-selectable at switch 152, by the reduced potential caused by relay 212 on conductor 165 as above described.

55 It will be noted that when trunk 155 was seized by switch 100, relay 122 was actuated in the manner described in detail in the above mentioned application of W. W. Carpenter.

60 With magnet 121 completely operated a circuit is completed for initiating the release of the marker and for setting certain of the contacts in switch 150. This circuit may be traced from ground at the

contacts of relay 122, contacts of switch 150, to battery through the operating winding of relay 118. Relay 118 operates in this circuit and extends the same ground through its armature and front contact to the sleeve conductor 165 of trunk 161, appearing before the power driven switch 152. Trunk 161 is thus rendered non-selectable at both the coordinate switch 150 and the power driven switch 152, and remains non-selectable after the disconnection of relay 212. The above traced ground is also extended by means of contacts of connector 180, conductor 257, right inner armature and contact of relay 210, contacts of relay 216, to battery through the winding of relay 215. Relay 215, in turn, closes obvious operating circuits for relays 213 and 214 in parallel. In the manner described in detail in the above mentioned application of W. W. Carpenter, the operation of relays 213 and 214 brings about the release of the marker, the sender connector 130, frame connector 140 and trunk connector 180 as well as the release of vertical magnets 156 and 157. The connection through switch 150 however is maintained by the continued energization of magnet 121 which is held through both of its windings in series to the grounded conductor of trunk 161.

65 The calling line having thus been extended to the trunk 161, the incoming switch 160 and the final switch 170 are selectively actuated under the control of the called line designation as recorded in the sender to connect with the called subscriber's line. The manner in which the sender controls the operation of the incoming and final switches is completely described in the copending application of W. W. Carpenter hereinbefore referred to.

70 What is claimed is:

1. In a telephone system, calling lines, automatic switches for extending said calling lines, trunks, each trunk appearing in a plurality of said switches, means for identifying a non-selectable trunk in the same manner at each of said plurality of switches, means for operating one of said plurality of switches to seize a trunk and place a non-selectable condition thereon at said plural 110

5. In a telephone system, calling lines, an automatic switch of the progressively movable type and an automatic switch of the coordinate type both of said switches being adapted to extend said lines, a trunk appearing before both of said switches, means for identifying a non-selectable trunk in the same manner at each of said plurality of switches, means for operating one of said switches to place a non-selectable condition on a trunk at said plurality of switches, means responsive to the operation of another of said switches to place a non-selectable condition on said trunk at said other switch alone, and means for preventing the seizure of a trunk which is in a selectable condition at said one of said switches and in a non-selectable condition at said other of said switches. 60
10. In a telephone system, calling lines, automatic switches of different types for extending said lines, trunks, each trunk appearing before different types of switches, means for identifying a non-selectable trunk in the same manner at the different type switches before which it appears, means for operating a switch of one type to seize a trunk and place a non-selectable condition thereon at another type switch before which said trunk appears, means for operating said other type of switch to seize said trunk and place a non-selectable condition thereon at said other type of switch alone, and means for preventing the seizure of a trunk which is in a non-selectable condition at one of said switches and in a selectable condition at another of said switches of a different type. 65
15. In a telephone system, calling lines, automatic switches of different types for extending said lines, trunks, each trunk appearing before different types of switches, means for identifying a selectable trunk at said different types of switches, said means being individual to a trunk and common to said different types of switches, means for identifying a non-selectable trunk in the same manner at said different types of switches, means for operating a switch of one type to place a non-selectable condition on a trunk at a switch of another type, means responsive to the operation of a switch of said other type to place a non-selectable condition on a trunk at said switch of said other type alone, and means for preventing the seizure of a trunk which is in a selectable condition at a switch of one type and in a non-selectable condition at a switch of another type. 70
20. In a telephone system, calling lines, an automatic switch of one type, an automatic switch of a second type both of said switches being adapted to extend said lines, a group of trunks each trunk appearing before a switch of each of said types, a testing and controlling mechanism associable with said first mentioned switch, means in said mechanism for performing a simultaneous test of all trunks in said group to set up a record of the condition of said trunks, means responsive to the completion of said setting for operating said first mentioned switch to seize an idle trunk, means responsive to the seizure of said idle trunk by said second mentioned switch for causing said setting to be revised, and means for causing said first mentioned switch to seize an idle trunk in accordance with said revised setting. 75
25. In a telephone system, calling lines, a progressively movable automatic switch, a coordinate automatic switch, a trunk accessible in common to both of said switches, a relay individual to said trunk normally effective to maintain the test conductor of said trunk at different potentials at each of said switches, means responsive to the seizure of said trunk by said coordinate switch for operating said relay to maintain the same busy potential on said trunk at both of said switches, and means responsive to the seizure of said trunk by said progressively movable switch for maintaining said busy potential on said trunk at said progressively movable switch alone. 80
30. In witness whereof, I hereunto subscribe my name this 6th day of November A. D., 1924.
35. WARREN W. CARPENTER.
